UNITED STATES PATENT OFFICE

122,592

DESIGN FOR A HEATER

Henry W. Fink, Chicago, Ill., assignor to Tropic-Aire, Incorporated, Chicago, Ill., a corporation of Delaware

Application July 7, 1939, Serial No. 85,878

Term of patent 3½ years

To all whom it may concern:

Be it known that I, Henry W. Fink, a citizen of the United States, residing at Chicago, county of Cook, and State of Illinois, have invented a new, original, and ornamental Design for a Heater, of which the following is a specification, reference being had to the accompanying drawing, forming part thereof.

In the drawing:

Figure 1 is a front elevational view of a heater showing my new design; and

Figure 2 is a top plan view.

The rear of the heater comprises a conventional opening through which air passes to the radiator.

I claim:

The ornamental design for a heater, as shown and described.

HENRY W. FINK.
